Int. Cl. D3—99

U.S. Cl. D87—1

FIG. 1 is a front elevation of a carrying bag for hand tools showing my new design;

FIG. 2 is a rear elevation thereof;

FIG. 3 is a side elevation thereof; and

FIG. 4 is a front perspective view thereof.

Portions of a conventional carrying strap have been omitted from the figures for convenience of illustration.

This is a continuation-in-part of design application Ser. No. 5,331, filed Jan. 6, 1967, and now abandoned.

I claim:

The ornamental design for a carrying bag for hand tools, substantially as shown and described.
